UNITED STATES PATENT OFFICE.

MARK JAY SAMUELS, OF NEW YORK, N. Y., ASSIGNOR TO LYRAPHONE COMPANY OF AMERICA, OF WASHINGTON, DISTRICT OF COLUMBIA, A CORPORATION OF DELAWARE.

TALKING-MACHINE.

1,284,463.

Specification of Letters Patent. Patented Nov. 12, 1918.

Application filed January 6, 1916. Serial No. 70,613.

To all whom it may concern:

Be it known that I, MARK JAY SAMUELS, a citizen of the United States, and a resident of the borough of Manhattan, city, county, and State of New York, have invented certain new and useful Improvements in Talking-Machines, of which the following is a specification.

One object of my invention is to provide a talking machine which shall be comparatively inexpensive in manufacture, and at the same time pleasing in appearance and efficient in operation.

Another object of my invention is to provide a talking machine which will effect a true, pure and accurate reproduction of tones or sounds, without the production of the false, harsh noises so often noticed in the operation of instruments of this character.

Another object of my invention is to increase the volume of sound emitted, by constructing the entire case and the sound amplifier of sheet metal, and by so connecting these parts that the case will vibrate in unison with the amplifier.

Another object of my invention is to construct the sound amplifier in such a way that it will have the requisite stability and at the same time will be readily responsive to vibrations of various frequencies.

Still another object of my invention is to provide air cushions for the vibrations of the amplifier, and thus eliminate all harshness of tone.

Other objects and advantages of my improved device will be pointed out in the specification and claims which follow.

Referring to the drawing, Figure 1 is a plan view, partly in section, of my improved talking machine, and

Fig. 2 is a side elevation thereof, partly in section.

The casing 5 of my improved device is preferably stamped from a single piece of sheet metal, the bottom of said casing being preferably enlarged as shown at 6 to provide a suitable base. Supporting legs are indicated at 7.

Mounted within the casing and preferably suspended from the top thereof, is the motor 8 which may be of any desired construction. This motor is adapted to impart rotary motion to the record supporting disk 9 which is mounted upon the spindle 10,

as is clearly shown. Means such as the handle 11 may be provided for winding the motor, and a suitable braking mechanism such as is indicated at 12 may be employed for controlling the rotation of the record supporting disk in a manner which is well understood.

The sound box 13 is provided with the usual stylus 14, which is adapted, when the device is in operation, to rest upon a record supported by the disk 9. The sound box 13 may be connected to the extension 15 of the sound amplifier 16 by any suitable tone arm 17. I prefer, however, to employ a flexible tone arm which is adapted to be connected to the extension 15 by a pin and slot connection such as is indicated at 18, such a tone arm and such connecting means being fully described in my co-pending application, Serial Number 62,979, filed November 23, 1915.

The sound amplifier 16, which is of substantially rectangular gradually increasing cross section, is constructed of sheet metal, the material being preferably the same as that employed in constructing the casing 5. The amplifier is located within the base 6 of the casing as shown, and is connected thereto at the rear and at the front whereby the casing and the amplifier vibrate in unison. In other words, by so constructing and connecting the amplifier and casing, I cause the entire casing to vibrate as a sounding board, and thus obtain a sound reproduction of great volume.

It is evident that if the top and bottom walls of the amplifier 16 were merely plane surfaces, they would lack the stability requisite to the accurate vibration thereof. I have therefore conceived the idea of bowing or buckling these surfaces as shown in Fig. 2, and I find that by thus maintaining the material of the amplifier under a certain degree of stress, I eliminate all false vibrations thereof.

As a means for insuring the accurate vibration of the amplifier, I preferably provide the top and bottom walls thereof with stiffening ribs such as are indicated at 19, 20, 21. These ribs are formed by indenting the walls from within and the several ribs are preferably of different lengths. For example, the rib 19, shown in Fig. 1, may extend continuously around the wall adjacent the four edges thereof, the rib 20, may extend longitudinally in the middle of the

wall, and the rib 21 may be substantially the same as rib 20, except that it is located nearer the edge and is of less length. By providing these ribs of various forms and 5 lengths, I find that the amplifier is rendered more readily responsive to vibrations of various frequencies, or, in other words, the accurate reproduction of both high and low tones is insured. The principle on which 10 such an amplifier operates is somewhat similar to the principle of operation of instruments of the type of the violin. Such instruments are practically always provided with S-shaped recesses in their upper surfaces. 15 These recesses divide the surfaces into component surfaces or sounding boards of various lengths, whereby the vibration thereof at various frequencies is facilitated.

In order to obviate the possibility of any 20 harshness in the tones reproduced, I preferably surround the amplifier with confined air spaces. These spaces serve as cushions for the vibrations, and thus eliminate all harshness. I preferably form these air 25 spaces by fitting, within the casing above the amplifier, a piece of corrugated material, such as pasteboard, as indicated at 22 in the drawing. This piece of material, in addition to its function of inclosing the air spaces, 30 operates also as a sounding board, and because of its texture serves to soften the tone emitted.

It is apparent from the foregoing that I 35 have produced a scientifically constructed instrument which will truly and accurately reproduce vocal as well as instrumental music, and will do so without the harsh, nasal sounds so often noticed in the operation of instruments of this character.

40 While I have illustrated and described but a single embodiment of my invention, it will be obvious to those skilled in the art, that many changes may be made therein without departing from the spirit of my invention.

What I claim is:

1. In a device of the character described, a metallic casing, a metallic sound amplifier and a motor inclosed therein, and a sheet of corrugated material fitted within said casing between the motor and the amplifier, whereby said amplifier is surrounded by a confined air space and is acoustically insulated from said motor, for the purpose described. 50

2. In a device of the character described, a metallic casing, a motor inclosed within said 55 casing, a metallic sound amplifier also inclosed within and secured to said casing, whereby the casing vibrates in unison with the amplifier, and a sheet of corrugated material fitted within said casing between 60 the motor and the amplifier, whereby said amplifier is surrounded by a confined air space, and is acoustically insulated from said motor, for the purpose described.

3. In a device of the kind described, a casing, a motor contained therein, a sound amplifier passing through the casing beneath the motor and a sheet of sound insulating material extending wholly across the casing and interposed between the motor and am- 70 plifier.

4. In a device of the kind described, a sound amplifier passing through the casing, a casing having an aperture in its upper side, a cover adapted to completely cover 75 said aperture, a motor suspended from said cover and a sheet of sound insulating material extending across the casing beneath the motor and separating the motor chamber from the amplifying chamber. 80

In testimony whereof I have signed this specification in the presence of two subscribing witnesses.

MARK JAY SAMUELS.
